CLAIM

The ornamental design for a door and window sensor component, as shown and described.

DESCRIPTION

FIG. 1 is a front perspective view of a door and window sensor component, according to the present design;

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken line showing in the figures illustrates portions of the door and window sensor component that form no part of the claimed design.

1 Claim, 4 Drawing Sheets
